UNITED STATES PATENT OFFICE

116,240

DESIGN FOR A COMBINED MANICURE STAND AND CONTAINERS THEREFOR

William B. Petzold, Pittsfield, Mass., assignor to General Electric Company, a corporation of
New York

Application May 13, 1939, Serial No. 84,979

Term of patent 14 years

To all whom it may concern:

Be it known that I, William B. Petzold, a citizen of the United States, residing at Pittsfield, in the county of Berkshire, State of Massachusetts, have invented a new, original, and ornamental Design for a Combined Manicure Stand and Containers Therefor, of which the following is a specification, reference being had to the accompanying drawing, forming a part thereof.

In the accompanying drawing, the figure is a perspective view of a combined manicure stand and containers therefor, showing my new design.

The sides of the stand opposite the sides shown are identical with the exception that there is no
cotton opening in the side opposite the front side.

I claim:

The ornamental design for a combined manicure stand and containers therefor, as shown and described.

WILLIAM B. PETZOLD.
